FRED W. GUNN, OF BOSTON, MASSACHUSETTS.

TOOL FOR APPLYING WIRE CLAMPS.

Application filed April 15, 1925. Serial No. 23,317.

My invention relates to improvements in tools for applying wire clamps to hose couplings or like objects, and it consists in the combinations, constructions and arrangements herein described and claimed.

An object of the invention is the provision of a simple, reliable and efficient tool which can be conveniently manipulated to firmly secure a wire clamp in place on a hose or like object.

A further object of the invention is the provision of a tool of the character described which affords facilities for twisting the ends of the tightened wire clamp to prevent loosening of the clamp and for causing the surplus material at the ends of the clamp to be broken off when the clamp is secured in place.

Other objects and advantages of the invention will be apparent from the following description, considered in conjunction with the accompanying drawings in which:

Figure 1 is a plan view of the improved tool in position for use in securing a wire clamp on a hose.

Figure 2 is a longitudinal vertical section through the tool, showing also in section the hose to which the clamp is being applied, and

Figure 3 is a transverse section through the tool, the view being taken substantially along the line 3—3 of Figure 1.

The improved tool comprises an elongated body 1 made of wood, metal, or any other suitable material. The body has an end portion thereof enlarged vertically as indicated at 2 to provide a clamping head. This clamping head preferably is circular in cross-sectional contour and tapers toward its outer end. The clamping head 2 is hollowed out to provide a twisting chamber 3 which is open at its outer end at the front end of the head and tapers rearwardly to a reduced opening 4 at the rearward end of the head.

The bottom wall of the opening 4 is substantially flush with the upper face 1^a of the adjacent portion of the body 1. A pin 5 extends transversely through the head 2 so that the upper part of the intermediate portion of the pin will be received in a transverse seat 6 in the upper wall of the rearward part of the twisting chamber 3 and will protrude from the seat 6 to a level slightly below that of the upper wall of the opening 4. The upper face 1^a of the body

1 adjacent to the head 2 is substantially flat for a short distance and then is formed with a downwardly inclined shallow groove 7 which is merged at its rearward end into an aperture 8 which extends longitudinally of the body 1 nearly to the rearward or outer end of the latter. The body 1 is preferably enlarged laterally from the rearward end of the groove 7 to the rearward end of the body, this laterally enlarged rearward end portion constituting a handle which is adapted to be firmly grasped in the hand.

The rearward end portion of this handle is formed with a groove 9 which extends from the rearward end of the aperture 8 for the remainder of the length of the handle along the longitudinal median line of the handle and opens through the upper face of the rearward end portion of the handle.

A wire tightening rod 10 has the forward end portion thereof flattened as indicated at 11, this flattened end portion being bent downwardly at its extremity substantially at right angles to the longitudinal axis of the rod 10 to provide a supporting end portion 12 which is adapted to bear on the substantially flat upper face of the forward end portion of the body and to then support the flattened portion 11 of the wire tightening rod 10 in spaced relation to the body 1. The wire tightening rod 10 is of sufficient length to extend rearwardly through the slot 9 beyond the rearward end of the handle portion of the body. The rearward end portion of the rod 10 is provided with screw threads 13. A concavo-convex bearing washer 14 is loose on the threaded end portion of the rod and is adapted to fit closely against the rearward end of the body 1. A tightening nut 15 is screwed onto the threaded end portion of the rod 10. The nut 15 can be turned on the rearward end portion of the rod 10 against the convex-outer face of the bearing washer 14 which is in contact with the rearward end of the handle portion of the body at the outer end of the slot 9 and it will be understood that further turning of the nut 15 on the threaded portion of the rod 10 will cause axial movement of the rod 10 in the direction opposite the clamping head 2.

The flattened forward end portion 11 of the wire tightening rod is provided directly at the rear of the supporting end portion 12 with a wire engaging vertical aperture 16.

From the foregoing description of the sired, these twisted together portions can be bent downward close to the hose. From the foregoing description, it will be understood that the tool is conveniently and easily operable to firmly secure a wire clamp in place on the object to which it is to be applied.

Obviously, the invention is susceptible of embodiment in forms other than that which is illustrated in the accompanying drawing, and I therefore consider as my own all such modifications and adaptations thereof that fairly fall within the scope of the appended claims.

I claim:

1. A tool of the character described comprising an elongated body, a clamping head at one end formed to permit the end portions of the wire clamp to be extended therethrough, said body having a substantially flat upper face at the rearward end of said clamping head, a wire tightening rod having the forward end portion thereof flattened and bent downwardly at its extremity to provide a supporting end portion adapted to slide on the upper face of said body, said flattened portion of the rod having a vertical aperture directly at the rear of said depending supporting portion to accommodate the end portions of the wire clamp, and adjustable means arranged between said rod and the rearward end portion of said body for causing axial movement of said rod on said body in the direction opposite to said head.
2. A tool of the character described comprising an elongated body having a clamping head at one end thereof, said clamping head having a chamber therein open at the forward end of the clamping head and having a reduced opening at its rearward end, the bottom wall of said reduced opening being substantially flush with the upper face of the adjacent portion of said body, and said body having a longitudinally extending aperture rearwardly of said clamping head, a wire tightening rod having the forward end portion thereof bent downwardly and adapted at its extremity to slide on the body between said clamping head and said aperture in the body, said wire tightening rod having a vertical aperture formed therein at the rear of said downwardly turned forward end portion, whereby the ends of a wire clamp may be projected through the aperture in said rod into the aperture in said body, a wire creasing pin extending transversely across the upper rearward part of said chamber adjacent to said reduced opening.

FRED W. GUNN.
